CLAIM

The ornamental design for an electrical receptacle lift-up structure, as shown and described.

DESCRIPTION

FIG. 1 is a perspective view of an electrical receptacle lift-up structure which embodies my design;

FIG. 2 is a front elevational view thereof;

FIG. 3 is a back elevational view thereof;

FIG. 4 is a top plan view thereof;

FIG. 5 is a bottom plan view thereof;

FIG. 6 is a right side elevational view thereof, the opposite side elevational view being a mirror image thereof; and,

FIG. 7 is a perspective view of an alternate embodiment of my design for an electrical receptacle lift-up structure.
